HANDLE FOR FOOTBALL DUMMIES

Herman Delmos Wynn, Knoxville, Tenn.

Application March 25, 1949, Serial No. 83,466

4 Claims. (Cl. 273—55)

1

This invention relates to improvements in handle structure for football dummies.

The object of this invention is the provision of improved means for very durably securing supporting and holding handles to football dummies.

Other objects and advantages of this invention will be apparent during the course of the following detailed description.

In the accompanying drawings wherein for the purpose of illustration are shown several forms of the improved football dummy—

Figure 1 is a side elevation of an improved bell-shaped or straight tapered sided dummy.

Figure 2 is a vertical cross sectional view taken thru the improved football dummy of Figure 1.

Figure 3 is a plan view of the football dummy.

Figure 4 is an enlarged fragmentary view showing the construction of a holding and supporting handle connected at each side of the dummy.

Figure 5 is a fragmentary view showing the body pattern of the dummy cover of Fig. 1.

Figure 6 is a fragmentary inside view of the top wall pattern of the dummy cover.

Figure 7 is a cross sectional view taken substantially on the line 7—7 of Figure 4.

Figure 8 is an enlarged fragmentary cross sectional view showing the manner of sewing an end wall to the body of the container cover.

Figure 9 is a side elevation of a straight vertical sided football dummy constructed according to the principles of the dummy illustrated in the other figures.

In the drawings, wherein similar reference characters designate corresponding parts throughout the several views, the letters A and B may designate respectively the forms of invention shown in Figures 1 and 9, and so far as applicable similar reference characters designate similar parts throughout the views showing the two forms of invention. In the form of invention A, an inflatable tube or bladder C is housed within a canvas cover D; the latter being provided with an improved handle structure D.

The cover D may be made of fabric or any other approved material of a flexible and durable nature. It includes a body wall structure 10, of frusto-conical shape, as shown in the fragmentary view, Figure 5; the marginal sides of which are folded inwardly and stitched to form a seam 11. A normally flat bottom wall 12 is inwardly lapped over the lower marginal portion of the base end of the body wall 10, and they are stitched together to form a joint 13, shown in Figure 2.

The inflatable bladder or tube C is preferably

2

of rubber or other synthetic material having a frusto-conical shaped tapered body wall 15, and bottom and top walls 16 and 17 respectively. The latter are normally flat when the tube is deflated.

5 The top wall 17 is centrally provided with a conventional air inlet and check valve F, which functions similar to a conventional tire valve and the stem of which extends axially of the tube C, as shown.

10 The top wall structure 20 of the textile covering D is formed of a pair of segments 21 and 22 (see Fig. 6), the chord edges of which are lapped or folded upon the under surface of the segments, as shown at 23 and 24 respectively, and stitched at 25 to hold the fold. The segment 22 reinforcing lap 24 terminates short of the circumferential edges of the segment, and there extension flaps 26 are provided which overlap upon the ends of the lap reinforcement 23 of the segment 21. Stitching 27 at these joints connects the segments 21 and 22 together, as shown in Figure 6. Thus the top wall 20 of the covering D is provided with a slit or opening 30 thru which the bladder or tube C may be inserted or removed.

15 Lacing eyelets or grommets 31 are provided along the lap reinforcements 23 and 24, as shown in Figure 6, for receiving a lacing cord 35, by means of which to draw the segments together and close the opening 30, as shown in Figure 3. The valve F may extend thru the slit when the dummy is assembled, or it may be folded inwardly beneath the cover, if desired.

20 A circular disc-shaped protecting flap 37 is stitched at 38 upon the under side of the segment 21 and this is folded over the under side of the top wall 20 beneath the slit or opening to protect the bladder from the lacing and eyelets, and from protruding thru the opening in the top wall. This flap 37 has a grommet or eyelet 39 thru which the stem of valve F may extend.

25 The top wall 20 is peripherally lapped over the top margin of the body wall 10, as shown in Figure 8 and this lap joint is stitched together as at 40.

30 One of the important features of this invention is the provision of a durable handle structure, capable of effectively withstanding the abuse to which the handles or holding straps of football dummies are subjected. It is well known that ordinary handles not only need frequent replacement, but are so flimsily attached that at times the entire external covering of the football dummy is destroyed.

35 The details of the handle structure E are shown in Figures 2, 4 and 7.

The handle assembly E comprises a strap handle 50 of flexible textile webbing doubled upon itself to provide a handle loop 60; the two end lengths of the webbing 50 being spread apart, as shown at 61 and 62, in Figure 4 of the drawings. For each of the handle structures E the cover wall 10 is provided with a slit or opening 63, shown in Figure 7, thru which the webbing 50 extends; the loop 60 lying exteriorly of the cover and the two divergent ends 61 and 62 lying upon the inside surface of the wall 10 and being double stitched thereto as at 65, for the entire lengths thereof.

For reinforcing purposes and as a protection for the bladder C, a flexible textile cover or flap 67, shown in outline in Figure 4, is marginally stitched as at 68 to the wall 10. The stitching 65 for the webbing 50 is also stitched thru this flap or cover 67.

In order to prevent tearing of the cover or jacket D at the location where the webbing handle extends thru the opening 63, a very strong reinforcing patch 70 is provided, having an opening 71 thru which the loop end of each handle 50 extends. The reinforcing patch 70 is preferably of thick leather or other material, having a very high tear resistance. The patch 70 is marginally stitched at 75 to the jacket wall 10 and the reinforcing patch 67; the stitching also extending across the branched portion of the webbing, as indicated in Figure 4. As an additional protection, a line of heavy stitching, shown at 77 in Figure 4 of the drawings, extends across the patch 70 and thru all of the underlying material and also across the handle 50 just above the point where the webbing extends thru the patch opening 71. This stitching will probably give way under extreme use at a location above where the loop extends thru the patch opening, but the same under ordinary usage is capable of supporting the dummy without rupture, so that direct strains need not be placed on the materials at the openings thru which the loop extends. Of course the patch and reinforcing assemblage is so constructed that, if the stitching 77 does tear loose at this location, the same will prevent tearing or ripping of any part of the handle structure, jacket or patch, even under conditions of extreme strain.

Two of the handle structures E are located at diametrically opposed sides upon the dummy A, and also upon the dummy B, at the upper ends of the dummies.

The structure of the dummy B, except for shape, is identical with respect to that above described for the football dummy A. The main difference is that the jacket D' has a straight vertical side and end wall structure, and the inflatable tube or bladder for the dummy B is similarly shaped.

It is within the scope of this invention to provide the football dummy of this invention of rubber or composition rubber impregnated flexible textile, capable in itself of sustaining a desired air pressure, and in which case the inflatable bladder structure need not be provided.

It will be apparent from the foregoing that an improved football blocking dummy has been provided of an extremely durable construction, without ballast and of little bulk when deflated.

Variations may be made from the structure described. For instance, the air valve could be provided in the side structure of the dummy if found desirable.

As above mentioned, the top and bottom walls 75 patch of flexible material having a slit opening

of both the jacket or covering and the inflatable bladder are normally flat when the structure is deflated, but these top and bottom walls will bulge outwardly in slightly rounded shape, as shown in the drawings, when the bladder is inflated.

Various changes in the shape, size and arrangement of parts may be made to the form of invention herein shown and described without departing from the spirit of the invention or the scope of the following claims.

I claim:

1. A handle structure for securement to the jackets of football dummies and the like comprising in combination with a flexible body portion having a slit therein, a handle webbing doubled upon itself and extended thru said slit opening to provide a hand loop portion externally of the body portion, the hand loop being intimately doubled upon itself and the ends of the webbing disposed internally within the body portion being laterally arranged in divergent relation towards the free ends thereof, and reinforcing means securing said divergent end portions to the body portion.

2. In a handle structure for attachment to the body casing portions of football dummies and the like, the combination of a body portion having a slit therein, a handle webbing doubled upon itself and extended thru said slit opening to provide an external hand loop and ends of the webbing overlying the inside of the body portion and stitched thereto, a reinforcing member externally upon the body portion surrounding said slit and secured to said body portion, and an internal reinforcing flap secured to the inner surface of the body portion and overlying the ends of the handle webbing and secured thereto.

3. A football dummy comprising a jacket structure having a slit-like opening therethru, a flexible webbing handle doubled upon itself to provide a loop and free ends, the free ends extending thru said slit opening to overlie the under surface of the jacket structure with the loop extending externally of the jacket structure, said ends being arranged in divergent relation upon the inner surface of the jacket structure, a covering patch secured to said jacket structure over the ends of said webbing, and a durable reinforcing patch of flexible material having a slit opening therein for receiving therethru the loop end of the webbing, said reinforcing patch lying exteriorly upon the jacket structure surrounding the slit opening of the jacket and being fixedly secured to said jacket structure.

4. A football dummy comprising a jacket structure having opposed handle structures secured therewith, the jacket structure for each of said handle structures having a horizontal slit opening therein between the top and bottom thereof, each of said handle structures including a flexible webbing doubled upon itself to provide a handle loop and two free ends, the free ends extending thru said slit and overlying the under surface of the jacket structure, with the handle loop extending externally of the jacket structure, said ends of the strap being arranged in divergent relation upon the inner surface of the jacket structure from the slit so as to cover an appreciable area thereof and being stitched and retained in such relation to said jacket structure, a covering patch secured to said jacket structure upon the inner surface thereof entirely covering the ends of said handle and extending across said slit to a point therebeyond, and a durable reinforcing

therein aligning with the slit of said jacket and receiving therethru the loop end of the webbing, said reinforcing patch externally bordering the slit opening of the jacket and being fixedly secured to the jacket structure.
